WALTER A. DORSEY, OF COLUMBUS, OHIO, ASSIGNOR TO THE BONNEY-FLOYD COMPANY,
OF COLUMBUS, OHIO, A CORPORATION OF OHIO.

MOUNTING FOR WHEELS AND AXLES OF MINE-CARS.

1,215,631.

Specification of Letters Patent. Patented Feb. 13, 1917.

Application filed June 29, 1915. Serial No. 37,085.

To all whom it may concern:

Be it known that I, WALTER A. DORSEY, a citizen of the United States, residing at Columbus, in the county of Franklin and State of Ohio, have invented certain new and useful Improvements in Mountings for Wheels and Axles of Mine-Cars, of which the following is a specification, reference being had therein to the accompanying drawing.

This invention relates to improvements in the devices for mounting the wheels and axles on the cars that are used in coal mines; and particularly to the cars of the class which have two wheels for each of two axles, each axle being rigidly connected to one of its wheels and loose and rotatable in the other.

The object is to provide a set of parts for connecting the wheels and the axles to the cars, which parts together with the wheels and the axles shall be standard duplicates with relation to corresponding parts respectively, and which can be used upon either side of the car as occasion may require. When assembled the parts of a set are simple in character, they being of such nature that they can be put together and taken apart at any place about the mine and at points remote from the shop without requiring skilled labor.

The axles in these car mountings as ordinarily made are of such nature that they must be applied in special manner; if one is broken or bent it requires the detaching of both the bearing boxes and the replacing of the same. Again, the axles through shoulders or collars, transmit the thrust from one side to the other in a way that I avoid.

In the drawings:

Figure 1 is a vertical transverse sectional view showing part of a car, one of the boxes and one of the wheels in vertical section and the other box and wheel in elevation.

Fig. 2 is a side view of the wheel, the axle and part of the car.

Fig. 3 is a vertical section taken transversely of the axle at the center of one of the boxes.

Fig. 4 is a perspective of one of the bearings or boxes.

Fig. 5 is a perspective of the rocking sleeve mounted in each of the bearings.

1 indicates the box or body of a coal car,

having the side walls 2, 2 and the bottom 3 formed of plank or suitable wooden pieces.

4 indicates the axle, it consisting of a smooth continuous surfaced cylinder from end to end. It is made from round steel shafting, and the design of this and of the correlated parts is such that it can be readily formed by merely cutting off sections or lengths such as are called for by the car and the track gage. It is not shouldered or provided with collars in the way frequently followed, as it has no direct bearing upon or contact with the bearings. It is provided with two similar bores or apertures 4^a, one near each end. It is of such length that one end of the axle can project suitably beyond the outer planes of one of the wheel hubs, the end at 5 being somewhat nearer the center of the car than the end at 5^a.

The wheels of the pair are indicated by 6 and 7, the one at 6 being secured rigidly to the axle by a bolt 9 passing through the hub 8 of the wheel and through the aperture 4^a in the axle. The wheel 7 is entirely loose on the other end of the axle, being held against displacement by a cotter key 10 or equivalent holder.

The curves in the tracks of coal mines are frequent and on short radii. The differential travel, peripherally, of the wheels is very marked, and it is desirable to eliminate the slippage which is demanded of the inside wheel when the car is passing around such curves. At the same time it is desirable to have the axle rotate to distribute the wear and strain and for other reasons. When the axle and wheels are made and connected in the way described the wheels rotate independently and the axle is kept continuously in rotation by the wheel with which it is connected.

Inasmuch as the axle is without shoulders or collars to engage with the inner sides of the bearing boxes, the car and the boxes secured thereto can adjust themselves laterally inward or outward as occasion demands. If the car moves onto a curve to the right the inertia carries the flange of the left hand wheel against its rail, and causes the car body with its load to tend to move in the same direction. In the construction shown this tends to throw the pressure away from the right hand wheel and toward the flange and hub of the left hand wheel, there being no collar or shoulder at the right hand end

of the axle inside of the box. This pressure I provide for by replaceable washers such as shown at 24 and 20 which are interposed between the left hand box and the hub of the left hand wheel, and between the inner end of the box and the inner end of the sleeve 18 hereinafter described and which when worn can be readily replaced by another. A similar construction is applied in the box of the right hand wheels.

The boxes or bearings may, as concerns their details be of any suitable form. In my structure the boxes and their adjuncts are duplicates for the right and left side of the car, they being indicated as entireties by 11 and 12. Each is formed of a cylindrical casing 13 with flanges 25 which are secured to the bottom 3 of the car by bolts 26; and at the inner end each has a closing wall 14 which is fitted as closely as possible to the axle; and at the outer end with a grooved flange 15. In the groove of this flange and in a groove or chamber in the end wall 14 are placed packings 17 and 16 to exclude dirt, grit and foreign material, and to avoid the escape of lubricant.

Within the casing 13 there is fitted a sleeve 18. This has a cylindrical interior bore or chamber but is convexed on its outer face, the diameters of this outer face gradually shortening from the center, longitudinally, toward the end, and prevent any binding or bending of the axle. At the center the sleeve snugly contacts with the inner surface of the outer casing 13.

These mountings, as above stated, are secured to the wooden parts of the coal cars, and the boxes are apt to be thrown out of correct alignment by the warpings and shrinkings of the wood. The axle carrying sleeves 18 compensate for this as they permit the sleeves to rock around axes transverse to the axle and adjust themselves to the proper positions where the axle will freely rotate.

In the chamber or space between the sleeves 18 and the axle are inserted rollers 21 in a continuous series loosely held in place. Between the inner end of the sleeve 18 and the wall 14 of the bearing box there is inserted a replaceable washer 20; and between this and the inner ends of the rollers 21 there is placed a washer ring 22 to take the wear and thrust of the rollers. The above specified replaceable washer 24 lies between the outer end of the sleeve 18 and the inner end of the hub 8 of the wheel; and between this washer and the outer ends of the rollers 21 there is a ring washer 23. Each sleeve 18 constitutes a thrust element by which the side pressure of the car body is communicated to the outside washer 24 and thence to the wheel hub independently of the axle and of the rollers 21.

When the parts are constructed and re-

lated in the way described the wear from the relatively movable parts in the bearings is taken, as above explained, by the outer washer 24 and that at 20.

It will be seen that all the removable parts of one of the sets constituting a mounting for an axle and its wheels can be detached from the car without the use of tools. It is merely necessary to draw the cotter key at 10 and thereupon the axle can be drawn toward the left, its free end first passing inward through the right hand box and then outward through the left hand box. If the bolt 9 be withdrawn from the hub and axle the latter can be slipped also through the wheel. If any of the elements of a bearing require attention or replacing they can be readily drawn out and as readily replaced while the boxes remain in position on the car; and the wheels can be left in alignment if they and the car are properly supported, as by jacks.

If it is desired to reverse the shaft, endwise, as, when it is found that wear has occurred on the journal part of the loose wheel, it is inverted in position, that is, the end shown at the left is first passed through the left hand wheel and box and then through those at the right, the bolt is passed through the aperture previously holding the cotter key, and the latter is inserted in the aperture previously holding the bolt. If it is found that either or both of the washers 24 and 20 in either or both of the boxes requires renewal it is a simple matter (while the axle is off) to withdraw the old washer, and insert a new one.

What I claim is:

1. In a mounting for a car axle and its wheels, the combination of the boxes secured to the car at points inside the wheels, the axle mounted in the said boxes and arranged to neither receive or transmit pressure longitudinally from or to the boxes, the wheel rigidly secured to the axle at one end and rotating therewith, the wheel loosely mounted on the axle at the other end and thrust elements within the boxes, the hub of each wheel being arranged to take from the said thrust element of the adjacent bearing the side thrust of the car exerted toward said wheel.

2. In a mounting for a car axle and its wheels, the combination of the boxes secured to the car at points inside the wheels, the axle mounted in said boxes and arranged to either receive or transmit pressure longitudinally from or to the boxes, the wheel rigidly secured to the axle at one end and rotating therewith, the wheel loosely mounted on the axle at the other end, thrust elements within the boxes, the hub of each wheel being arranged to take from the said thrust element and adjacent bearing the side thrust of the car exerted

toward said wheel, and the removable wearing washer interposed between the hub and the adjacent bearing.

3. In a mounting for the axle and its wheels of a mine car, the combination of the boxes at the sides of the car, the axle adapted to be passed loosely longitudinally from end to end through the boxes, the wheel rigidly secured to the axle, the wheel loosely mounted on the axle and thrust elements within the boxes, the hub of each wheel being arranged to take from the said thrust element and adjacent bearing all the side thrust of the car exerted toward said wheel.

4. In a mounting for the axle and its wheels of a mine car, the combination of the boxes secured to the car, the axle adapted to be passed loosely longitudinally through the boxes from side to side of the car, the wheel rigidly secured to the axle and rotating therewith, the wheel loosely mounted on the axle, thrust elements within the boxes, the hub of each wheel being arranged to take from the said thrust element and adjacent bearing the side thrust of the car exerted toward said wheel, and the removable wearing washer interposed between the hub and the adjacent bearing.

5. In a mounting for a car axle and its wheels, the combination of the boxes secured to the car at points inside of the wheels, the axle mounted in said boxes and arranged to neither receive or transmit pressure longitudinally from or to the boxes, the wheel rigidly secured to the axle at one end and rotating therewith, the wheel loosely mounted on the axle at the other end, the hub of each wheel being arranged to take from the adjacent bearing the side thrust of the car exerted toward said wheel, the interposed axially acting thrust device between the bearing and the hub, the anti-friction devices between the bearing and the axle, and the removable wearing washers respectively interposed between the bearing and the axially acting thrust device and between the latter and the hub.

6. In a mounting for the axle and its wheels of a mine car, the combination of the boxes at the sides of the car, the reversible axle adapted to be passed loosely longitudi-

nally from end to end and in either direction through the boxes transversely of the car, the wheel removably and rigidly secured to the axle and the wheel loosely mounted on the axle, the hub of each wheel being arranged to take from the adjacent bearing all the side thrust of the car exerted toward said wheel.

7. In a mounting for a car axle and its wheels, the combination of the boxes secured to the car at points inside of the wheels, the reversible axle adapted to be passed loosely longitudinally and in either direction through the boxes transversely of the car, the wheel removably and rigidly secured to the axle relatively near one end and the wheel loosely mounted on the axle at transverse lines relatively farther from the opposite end, the hubs of the wheels being arranged to take respectively from their adjacent bearings the side thrusts of the car, substantially as set forth.

8. In a mounting for a car axle and wheels, in combination: the boxes secured to the car at points inside of the wheels, the axle adapted to be inserted longitudinally through the boxes, the thrust members around the axle and adapted to rock in the boxes to accommodate the same, and the wheels removably held on the axle to the hubs of which wheels the side pressure of the car body is applied through the said thrust members.

9. In a mounting for a car axle and wheels, in combination: the boxes secured to the car at points inside of the wheels, the axle adapted to be inserted longitudinally through the boxes, the rollers around the axle, the thrust members around the rollers and adapted to rock in the boxes to accommodate the axle, the washers at the ends of the thrust members, and the wheels removably held on the axle to the hubs of which the side pressure of the car body is applied through the said thrust members.

In testimony whereof, I affix my signature, in presence of two witnesses.
